UNITED STATES PATENT OFFICE.

JULIUS BING, OF EISENACH, GERMANY.

MAGNETIC CHUCK.

Application filed August 6, 1923. Serial No. 656,089.

To all whom it may concern:

Be it known that I, JULIUS BING, a citizen of the German Empire, residing at 18 Fischweide, Eisenach, Germany, have invented certain new and useful Improvements in Magnetic Chucks, of which the following is a specification.

My invention relates to improvements in magnetic chucks. Magnetic chucks such as 10 are now in use are made from cast steel or gray iron blocks the dimensions of which correspond to the desired size of the chuck. Therefore numerous blocks of different sizes must be kept in store corresponding to apparatus of the desired sizes or types, which 15 causes high running expenses. The object of the improvements is to reduce the running expenses by composing electromagnetic chucks of different sizes and forms from 20 a small number of standard cast iron or cast steel blocks. In the practice of the invention I compose the chucks from three or more parts, the median part being the main body of the chuck and consisting of 25 magnetic material and being substantially of even cross-section throughout its length. Only a small number of such main bodies need be kept in store, all of the said bodies being distinguished substantially by their 30 cross-sections. According to the desired size of the chuck a main body of the proper cross-section is taken, which is reduced to the length corresponding to the desired form of the chuck. Thereafter the magnetic coil 35 is placed into the cut-out parts of the body, caps are secured to the open ends of the body, and finally a cover is placed on the parts, which can readily be cut to the proper length.

40 In order that my invention be more clearly understood an example embodying the same has been shown in the accompanying drawings, in which the same reference characters have been used in all the views to indicate 45 corresponding parts. In said drawings,

Fig. 1, is an elevation partly in section showing the chuck with the median part broken away,

Fig. 2, is a top plan view partly in section,

Fig. 3, is a vertical cross-section taken on the line 3—3 of Fig. 1, and

50 Figs. 4 and 5, are elevations on a reduced scale showing two chucks of different lengths, the median parts being cut from the same cast iron block.

In the example shown in the figures the body of the chuck is made in three sections, a median section 1 and two end sections 2 and 3 in the form of caps. The median section consists of a body of magnetizable material such as cast steel or gray iron in the form of the letter "m" and having a web or body portion 4, flange portions 6, 6 and a core 5, the cross-section of the body being substantially the same all over the length thereof. The flange portions 6, 6 and the core 5 have the same height.

The end portions 2 and 3 are made from non-magnetic material such as brass or 70 aluminum and they are in the form of semi-cylindrical caps having their open sides at the sides of the body 1 and equipped with flanges 7 and 8. The end portion 3 is formed with a tubular portion 9 projecting 75 outwardly and in the direction of the longitudinal axis and having a cylindrical cap 10 secured thereto. Fitted in and insulated from the bottom of said box are two contact pins 11 having the terminals 12, 12 of a 80 magnetic coil 13 secured thereto. As shown the said coil is enclosed within a waterproof sheath made for example from a lead plate having its seams soldered and formed with a tubular portion 15 passed through the tubular portion 9 and having a flange 16 clamped in a tight way between a flange 17 of the member 10 and the adjacent margin of the portion 9 by means of screws 18.

In assembling the chuck the coil 13 embedded within the sheath 14 is placed around the core 5 and between the same and the flanges 5, and a plate 19 having the same length and the same breadth as the body 1 is placed on the same, which plate consists of two outer portions 20, 20 and an inner portion 21 both of magnetic material and corresponding respectively to the flanges 6, 6 and the core 5, and of narrow lamellæ 22 and 23 fitted between the said portions 20 and 21 and alternately made from magnetic and non-magnetic material. The portions 20, 21 and 22, 23 are made from standard bars cut in each case to the length corresponding to the type of the chuck, and they are connected with each other by bolts 27. The caps 2 and 3 are secured to the body 1 and the top plate 19 respectively by means of screws 24 and 25, and the top plate 26 is fixed in position by means of screw bolts 110 26 passed through the core 5.

If it is desired to manufacture a chuck

of the same breadth, which, however, is reduced in length, I reduce a standard body 1 in length by cutting therefrom a part 5 of its length and I place thereon a coil 13 of reduced length. Further, the plate 19 is made from strips or lamellæ cut from the standard bars to the proper length. The remaining parts generally need not be changed in form, with the exception that 10 the vertical corners of the core 5 at the face of the cut preferably will be rounded as indicated at 29 in Fig. 2.

It will be understood that by means of 15 a few castings of standard size a large number of chucks of different sizes may be manufactured, whereby the expenses of the manufacture are considerably reduced.

I claim:

1. An electro-magnetic chuck, consisting 20 of a channel-like body of magnetizable material formed with a web between the channel flanges and having substantially the same cross section all over its length, electric energizing means within said body, a 25 pole piece composed of magnetizable and non-magnetic portions, secured to the flanges and the web of said body, coil covering caps secured to the end faces of said body, and means for leading electric current 30 to said energizing means.
2. An electro-magnetic chuck, comprising an iron body formed with lateral flanges and a core portion between said flanges, said 35 flanges and core projecting from the body to the same side and the cross-sections of said body together with said flanges and core portion all over the length of the body having substantially the same configuration, an

electric coil mounted on said core portion, a slab-like pole piece having substantially 40 the length of said body covering the flanges and core portion of the body, and caps secured to the end faces of said body for covering the coil.

3. An electro-magnetic chuck, comprising 45 a body of magnetizable material having flange and core portions projecting to the same side and having the same cross-section throughout its length, an electric coil mounted on said core portion, a pole piece 50 composed of magnetizable and non-magnetic portions and connecting the flange and core portions of said body, and caps secured to the end faces of said flanges and of said pole piece for covering the coil. 55

4. An electro-magnetic chuck, comprising a body of magnetizable material having flange and core portions projecting to the same side and having the same cross-section throughout its length, an electric coil 60 mounted on said core portion, a pole piece composed of magnetizable and non-magnetic portions and connecting the flange and core portions of said body, and semicylindrical caps secured to the end faces of said 65 flanges and of said pole piece for covering the coil, one of said caps being formed with a tubular portion having the terminals of said coil passed therethrough.

In testimony I affix my signature in presence of two witnesses.

JULIUS BING.

Witnesses:

RUDOLPH FRICKE,
WILLY STIER.
